UNITED STATES PATENT OFFICE.

WALTER L. FOSTER, OF WHITTIER, CALIFORNIA, ASSIGNOR TO WILLIAM MEREDITH AND W. H. TAYLOR, BOTH OF HUNTINGTON BEACH, CALIFORNIA, AND V. W. BAILEY, OF PASADENA, CALIFORNIA.

AUTOMATIC PUMP CONTROL.

Application filed May 21, 1923, Serial No. 640,547. Renewed August 30, 1924.

To all whom it may concern:

Be it known that I, WALTER L. FOSTER, a citizen of the United States, and resident of Whittier, in the county of Los Angeles and State of California, have invented new and useful Improvements in an Automatic Pump Control, of which the following is a specification.

This invention relates to automatic controls for boiler feed pumps of the character illustrated and disclosed in United States Patents 1,270,138, dated June 18, 1918, and 1,302,350, dated April 29, 1919. The object of this invention is to provide details of structure whereby the durability, simplicity, and economy of structure are increased and the liability of trouble in operation decreased.

These objects together with other objects and corresponding accomplishments are obtained by means of the embodiment of my invention illustrated in the accompanying drawing, in which:

Fig. 1 is a central sectional view through the control; Fig. 2 is an enlarged view of a fragment of the valve linkage; Fig. 3 is a section as seen on the line 3-3 of Fig. 1; and Fig. 4 is a section as seen on the line 4-4 of Fig. 2.

Referring more particularly to the drawing, an equalizing chamber is indicated by 5. This chamber is preferably of cylindrical form and has a bottom in which a stuffing box 6 is disposed. A nipple 7 is provided in the bottom to which a pipe 8 is adapted to be engaged and connected with a boiler below the water level. Slidably extending through the stuffing box is an adjusting rod 9 for the bucket. Secured by bolts to the top of the chamber 5 is a head 10. The head has a dome portion 11 and a valve mechanism chamber 12. This chamber has a passage closed by a head 13 provided with a threaded nipple to receive a pipe 14 adapted to be connected to the steam dome of a boiler. Connected to the valve chamber is a whistle indicated generally by 15. A fitting 16 connects the valve chamber with a steam line leading to a boiler feed pump.

Disposed within the equalizing chamber is the bucket 17 which is hollow to form a

float. The bucket is mounted upon a rod 18 which is pivotally connected at its upper end to a lever 19. The lever is bifurcated at its other end by having a long slot formed therein. Extending into the slot is the head of a post 20, the lever 19 being connected thereto. Post 20 is adjustable so that it may be raised and lowered. Valve fitting 16 is provided with a seat 21 for a valve 22. The latter is conical in form and has a guide and adjusting stem 23 extending through a spider 24. The valve is pivotally connected to the lever 19. Extending through the slot in lever 19 is the stem 25 of the whistle valve so arranged that as the lever 19 drops to its lower position, it engages the head on the stem and opens the whistle. A link 26 is pivotally connected to the lever at one end and to a lever 27. The lever 27 is pivotally mounted in the head by means of a pin 28. At the end of the lever is a link 29 supporting a weight 30 mounted within the dome 11. It is obvious that the weight 30 acts through lever 27 to tend to raise the lever 19 and thereby close the valve 22 so as to cut off the supply of steam to the pump.

The bucket float 17 is open at the top so that it may be filled with water. When the bucket is entirely submerged in the water its weight is comparatively small and the counter weight 30 will raise the lever 19 so that the valve 22 may be closed upon its seat so far as permitted by reason of an adjustable stop 31 in the valve fitting which is engaged by the end of the valve stem 23. As soon as the water level drops so that part of the bucket is above the water, the added weight becomes great enough to overcome the action of the counter weight 30 and the bucket float is moved downwardly, thereby moving the valve 22 from closed position and admitting more steam to the feed pump. The bucket can be moved upwardly and downwardly upon the rod 18 by means of the rod 9 so that the position of the water level with respect to the valve may be adjusted. The position of the valve 22 may also be adjusted by means of the post 20. Thus, a fine adjustment of the water level and valve is provided. The whistle is to indicate low water. When due to lack

of water, the bucket 17 drops, it draws the lever 19 downwardly into its lowest position engaging the head on stem 25 and opening the valve controlling the steam for the 5 whistle.

What I claim is:

1. A boiler feed control comprising an equalizing chamber having a water connection at the bottom, a head affording a dome 10 and valve mechanism chamber, a steam connection communicating with said chamber, a port in said chamber communicating with a steam pump connection, a valve controlling said port, a valve lever for operating said 15 valve, an adjustable pivot post to which said lever is connected, a bucket float in said equalizing chamber secured to said valve lever and tending to open said valve, a weight lever pivotally mounted in said head and secured at one end to said valve lever, and a counter-weight disposed in said dome 20

and acting upon the other end of said weight lever.

2. A boiler feed control comprising an equalizing chamber having a water connection at the bottom, a head for said chamber, a steam connection communicating with said head, a port in said head communicating with a steam pump connection, a valve controlling said port, a valve lever for operating 25 said valve, an adjustable pivot post to which said valve lever is connected, a bucket float in said chamber secured to said lever and tending to open said valve, a weight lever pivotally mounted in said head and secured at one end to said valve lever, and a counter-weight acting upon the other end of 30 said weight lever.

In witness that I claim the foregoing I have hereunto subscribed my name this 3rd 40 day of May, 1923.

WALTER L. FOSTER.
